UNITED STATES PATENT OFFICE.

HENRY W. CAIRNS, OF DETROIT, MICHIGAN.

CHANGEABLE-SIGN DEVICE.

Application filed June 15, 1920. Serial No. 389,089.

To all whom it may concern:

Be it known that I, HENRY W. CAIRNS, a citizen of the United States, residing at Detroit, in the county of Wayne and State 5 of Michigan, have invented a new and useful Changeable-Sign Device, of which the following is a specification.

This invention relates to changeable sign devices, and more particularly to devices for 10 successively exhibiting signs carried by a web mounted on suitable rollers.

It is an object of the invention to provide an automatic mechanism driven by the motor which actuates the rollers for starting said 15 motor at substantially uniform time intervals, and for stopping the same after a travel of the web sufficient to register a different sign with the display opening of the device.

20 A further object is to automatically reverse the motor by means of a suitable step-by-step mechanism upon a travel of the web in either direction sufficient to complete display of all of the signs.

25 Among the distinctive features of the invention are the means employed to effect illumination of the sign, and the provision for variation in the speed of the rollers relative to the driving means therefor to compensate for the varying driving effect of 30 the web upon the reel from which it is being unwound.

The aforesaid objects are attained by the construction hereinafter described and illustrated in the accompanying drawings, 35 wherein,

Fig. 1 is a front elevation of the invention.

Fig. 2 is a side view of the same in partial section.

Fig. 3 is a detail in horizontal cross-section of one of the uprights of the frame, the section being taken on line 3-3 of Fig. 1.

Fig. 4 is a similar view of the lower cross 45 member of the frame, the plane of section being indicated at 4-4 in Fig. 1.

Fig. 5 is a rear view of the device upon a somewhat larger scale than that of Fig. 1, certain parts being broken away to more 50 clearly show portions of the operating mechanism.

Fig. 6 is a detail view of a step-by-step mechanism for controlling the motor circuits, including a diagram of said circuits.

55 Fig. 7 is another view of said mechanism transverse to Fig. 6.

In these views the reference characters 1 and 2 designate upper and lower rollers, and 60 3 is a web arranged to wind alternately from one to the other of said rollers, and carrying a plurality of advertisements or other signs. Said web, in traveling between said rollers, is exposed through a large rectangular opening 4 formed in a frame 5, the proportions of said opening being such that 65 the signs on the web are adapted to be individually framed therein, as best seen in Fig. 1. The uprights of the frame 5 are preferably angle bar trusses (see Fig. 2) and these are rigidly connected at top and bottom by angle bars 6. There is also extended between the upper ends of said trusses an ornamental vertical plate 7 carrying a clock 8, the dial of which is framed in said plate, as seen in Fig. 1. A pilaster effect 70 is given to each of the uprights of the frame by pressed sheet metal members 9, which serve also to conceal electric lamps 10 and to reflect the light thereof upon the displayed sign to illuminate the same. Lamps 11 are 75 also provided above and below the sign to illuminate the same, and sheet metal members 12 serve to conceal said lamps to reflect the light thereof upon the sign and to add to the ornamental appearance of the 80 frame.

The rollers 1 and 2 are mounted loosely upon shafts 13 journaled in the frame and are concealed behind the members 12. A driving connection from each of said shafts 90 to the corresponding roller is established by a coiled spring 14 recessed within one end portion of the roller, the connections of said springs to the rollers and shafts being reverse so that the tension on one of said 95 springs is being relieved while that of the other is increased, when both shafts are similarly driven. A motor 15 drives the lower shaft 13 through a speed reduction gearing 16, and the upper shaft 13 is driven from 100 the lower through an endless chain 17, the speed and direction of travel of the two shafts being the same. It is preferred to arrange the motor 15 and drive gearing 16 at one side of the frame 5, and at the other 105 side thereof to arrange within a casing 18 an automatic motor control mechanism which will now be described. Thus, upon an end of the lower roller 2 there is mounted fast a disk 19 from which a pin 20 projects radially. An adjacent disk 21 carries upon one of its side faces a plurality of 110

equally spaced pins 22, one of which is engaged by the pin 20 of the disk 19 for each revolution of the latter, so as to impart to said disk 21 a gradual step-by-step rotation. Adjacent the disk 21 is mounted a third disk 23 which has imparted thereto from the disk 21 a still more gradual step-by-step rotation. This is effected by providing upon a side face of said disk 23 a plurality of equally spaced pins 24 equal in number to the signs on the web 3, which pins are successively engageable by a radially projecting pin 25 upon the disk 21. As shown, there are ten pins 22 upon the disk 21, and seven pins 24 upon the disk 23. Thus ten revolutions of the initial driving disk 19 are required to effect a single turn of the disk 21, and seven turns of the latter are necessary to accomplish a revolution of the disk 23, seven being also the number of signs carried by the web 3. The disk 21 forms a control means for a switch 26 in the motor circuit 27, energized from the leads 27^a and 27^b, and the disk 23 is adapted to control a reversing switch in series with the switch 26, and comprising a pivotal switch arm 28 and a pair of contacts 29 and 30, a forward or reverse drive of the motor being effected according as said arm engages the contact 29 or 30. A radial pin 31 on the disk 21 is engageable with the switch 26 to open the same as said pin reaches its uppermost position, and a pair of radial pins 32 adjacently mounted upon the dial 23 are, one or the other, engageable with the switch arm 28, according to the direction in which said disk is being driven, to throw said switch arm from one to the other of the contacts 29 and 30 upon completion of a revolution of said disk. To insure immediate stopping of the disk 21 when the pin 31 opens the switch 26 and thus deenergizes the motor 15, a coiled spring 33 is mounted upon the stub shaft 34 of said disk so as to bear upon the latter and exercise a braking effect. Thus, after the disk 21 has completed a revolution and opened the switch 26, it remains in a position to hold said switch open until the motor 15 has been started again by the means which will now be described. A normally open switch 35 controls a shunt 36 around the switch 26, and is itself controlled by an electro-magnet 37, being closed when said magnet is energized. The circuit 38 of said magnet includes a hand 39 which rotates at a constant gradual rate, as for example, one revolution per minute. Said hand may conveniently be driven by one of the spindles (not shown) of the clock 8. Once in each revolution said hand encounters a contact 40, also in the circuit 38, so that the electro-magnet 37 is energized during the brief period of contact of said hand with said contact. During this brief period, therefore, the switch 35 is closed and the motor is started. Before de-energization of the magnet 37, and consequent opening of the switch 35, the disk 21 will have received at least one rotative impulse, causing it to disengage the switch 26 and permit the latter to close. Thus the switch 26 will continue to close the motor circuit subsequent to opening of the switch 35, and will maintain said circuit closed until the completion of ten revolutions of the roller 2 and disk 19, and a resultant single revolution of the disk 23, whereupon the pin 31 again opens the switch 26. The proportioning of the size of the signs on the web 3 to the diameter of the roller 2 is such that the travel of the web 3 accompanying ten revolutions of the roller is just sufficient to frame a different sign in the opening 4. As the number of convolutions of the web upon said roller increases, the travel of the web will of course be correspondingly increased, but a differential spacing of the signs on the web will compensate for this varying travel, so that ten revolutions of the roller will always be a measure of the travel of the web necessary to effect a change of signs. While completing each seven consecutive revolutions the disk 21 actuates a complete revolution of the disk 23. Since each revolution of the disk 23 effects the display of a different sign and there are seven signs on the web, they will be all displayed during the period required to effect one revolution of the disk 23. In completing its revolution said disk acts upon the switch arm 28, through one of the pins 32, and shifts the same from one to the other of the contacts 29 and 30, according to the direction in which said disk is driven. Thus after a step-by-step travel of the web 3 in one direction sufficient to display all of the signs thereupon, an automatic reversal of the motor 15 is effected so that a step-by-step travel of the web in a reverse direction takes place. While there has been shown and described an embodiment of the invention particularly adapted for large outdoor displays, it is of course to be understood that the same mechanism might be employed for actuating a smaller device.

What I claim is:

1. In a changeable sign, the combination with a pair of rollers and a web mounted thereon carrying a plurality of signs, of a frame provided with an opening across which said web travels, said opening being proportioned for the display of said signs individually, a motor having a driving connection with one of said rollers, a normally open switch controlling the motor circuit, a shunt around said switch, a second normally open switch in the shunt circuit, means for closing said second switch for short periods at regular time intervals,

- to initially energize the motor, and mechanism driven by the motor initially effecting closing of the first-mentioned switch and opening the same and holding it open upon a travel of the web sufficient to display a different sign through said opening.
2. In a changeable sign, the combination with a pair of rollers and a web extending between said rollers to alternately wind from one to the other, said web carrying a plurality of signs, of a frame provided with an opening across which said web travels, said opening being proportioned for the display of said signs individually, a motor having driving connection with said rollers, allowing a speed differential therebetween, a normally closed reversing switch controlling said motor, a normally open switch for the motor in series with said reversing switch,
- a step-by-step mechanism driven by the motor and having a cycle of operation initially effecting closing of said normally open switch and finally opening the same, said mechanism completing its cycle during travel of the web sufficient to effect a change of signs, means for initially energizing the motor at regular time intervals for periods sufficient to insure closing of the normally open switch, and a step-by-step mechanism driven by the motor in a relatively protracted cycle throwing over the reversing switch upon completion of said cycle, such completion being effected in substantial unison with completion of the desired travel of the web in either direction. 35

In testimony whereof I sign this specification.

HENRY W. CAIRNS.
